UNITED STATES PATENT OFFICE

CORTLAND W. DAVIS, OF OAK PARK, AND FRED F. BECKER, OF CHICAGO, ILLINOIS

DESIGN FOR A HEAT-INSULATED RECEPTACLE

Application filed January 10, 1929. Serial No. 29,568. Term of patent 14 years.

To all whom it may concern:

Be it known that CORTLAND W. DAVIS and FRED F. BECKER, citizens of the United States, and respectively residing at Oak Park and Chicago, in the county of Cook and State of Illinois, have invented a new, original, and ornamental Design for Heat-Insulated Receptacles, of which the following is a specification, reference being had to the accompanying drawing, forming part thereof.

The figure is a view in elevation of a heat-insulated receptacle, showing our new design.

We claim:

The ornamental design for a heat-insulated receptacle, as shown.

In testimony whereof we affix our signatures.

CORTLAND W. DAVIS.
FRED F. BECKER.
